WALDEMAR F. MAYER, OF PHILADELPHIA, PENNSYLVANIA, ASSIGNOR TO TAYLOR-
WHARTON IRON AND STEEL COMPANY, OF HIGH BRIDGE, NEW JERSEY, A COR-
PORATION OF NEW JERSEY.

HYDRAULIC PUMP OR MOTOR.

Application filed November 12, 1919. Serial No. 337,421.

To all whom it may concern:

Be it known that I, WALDEMAR F. MAYER, a citizen of Switzerland, residing at Philadelphia, in the county of Philadelphia and 5 State of Pennsylvania, have invented certain new and useful Improvements in Hydraulic Pumps or Motors, of which the following is a specification.

This invention relates to an improvement 10 in fluid gears of a multiple radial cylinder type, and is more particularly directed to a plunger connection to the crank pin, whereby a true line motion is given to the plungers to thereby insure the most even torque pos- 15 sible in a multi-cylinder crank-pin construc-
tion.

The invention, generally stated, consists in providing the crank pin with a freely-rotatable block, and securing the plungers di- 20 rectly and rigidly to this block, the cylinders for the plungers carrying cross-heads serv-
ing as valves to control the admission of the motive fluid to and its discharge from the cylinders.

25 In the drawings:

Fig. 1 is a view in elevation, partly in section, illustrating the improved fluid gear.

Fig. 2 is a section of the same on line 2-2 of Fig. 1.

30 Fig. 3 is a section on line 3-3 of Fig. 1.

The improved fluid gear comprises a casing 1, secured in an appropriate manner to a base 2. The casing, which is cylindrical in form, is constructed to provide two interior 35 concentric channels 3 and 4, having respective outlets 5 and 6, these channels serving as the usual fluid channels.

A drive shaft 7 is mounted in bearings secured to the casing, and immediately be- 40 yond one face of the casing such shaft is provided with a crank pin 8. Secured to the face of the casing 1 are valve casings 9, such being here shown as circular plate-like bodies, bolted at 10, in appropriately-re- 45 cesses portions 11 of the casing 1. The valve casings are of course arranged concentric with the drive shaft, and equal in number the desired number of cylinders, and are provided with channels 12 and 13 and 50 bore 14 to thereby provide a slide bearing for a cross-head 15. The cross-head is formed with a transverse opening 16, in which the open-ended cylinder 17 is secured, as by a threaded connection.

The valve casing is in open communication 55 with the channels 3 and 4, through ports 18 and 19, respectively, the latter, leading from the channel 4, including in part a channel 20 formed in the meeting faces of the valve casing and main casing, to thereby 60 dispose the ports 18 and 19, in their outlets within the valve casing, in the same line. The ports 18 and 19 open above the cross-head 15, and the movement of the latter is such as to align the cylinder 17, with the 65 respective ports 18 and 19 successively. That portion of the valve casing between the ports 18 and 19 constitutes an abutment, adapted in what may be termed the dead center position of the plunger within the 70 cylinder to close the cylinder.

Plungers 21 are arranged in the cylinders 17, and such plungers are connected to the crank pin in a manner to induce a valve operating function of the cross-heads 15 in the 75 operation of the parts. The crank-pin 8 is provided with a block 22, mounted thereon through the intermediate bushing 23. The plungers 21 are terminally threaded and thus fixed cooperate with threaded openings 80 in the block, as at 24.

The plungers may be flattened, as at 25, to permit application or removal from the block connection, and the fluid channels, or the outermost one thereof, may have straight 85 portions, as 26, to correspond with the straight line movement of the cross-heads.

The drive shaft 7 may be provided with a gear 27, keyed thereon, whereby power may be transmitted from said shaft, or the shaft may be extended beyond the end bearing for connection with other machines to be operated.

A characteristic feature of the present structure is that the working parts are 95 readily accessible without dismantling the entire structure. The plungers may be readily disconnected from the crank-pin block, the cylinders and cross-heads re-
moved from the valve casings, and the working parts thus disconnected and removed 100 for repair or renewal without any extensive disconnection of the gear as a whole.

Having thus described the invention, what is claimed as new, is:—
1. A fluid gear comprising cross-heads 105 mounted for reciprocation and serving as valves, a cylinder removably connected to

- each cross-head, a plunger operative in each cylinder, and means for inducing a movement of the plungers to compel a valve serving movement of the cross-heads.
5. A fluid gear comprising cross-heads mounted for reciprocation and serving as valves, a cylinder removably connected to each cross-head, a plunger operative in each cylinder, and a crank for inducing a movement of the plungers to compel a valve serving movement of the cross-heads.
10. A fluid gear comprising a main casing formed with concentric interior fluid channels, a drive-shaft mounted in bearings carried by the casing and having a crank-pin, valve-casings secured to the face of the casing and having ported communication with the respective channels, a block mounted on the crank-pin, plungers rigidly secured to the block, cylinders in which the plungers operate, and cross-heads carried by the cylinders and operating in the valve-casings to control the communication between the cylinders and the interior channels of the casing.
15. A fluid gear comprising a circular main casing, valve-casings removably secured to the face of such main casing, each of said valve casings having a cross-head bearing beyond the face of the main casing, cross-heads operative in said bearings, and means including cylinders and pistons therein for operating said cross heads for use as valves in said valve casings.
20. A fluid gear comprising a circular main casing, a drive-shaft mounted centrally thereof, valve-casings removably secured to the face of the main casing and having cross-head bearings formed therein outwardly beyond the face of the main casing, plungers operated by the drive shaft, cylinders in which the plungers operate, and cross-heads secured to the cylinders and operative in said bearings of the valve casings, the plungers, cylinders, cross-heads, and valve casings being thus arranged beyond the face of the main casing for accessibility.
25. In testimony whereof I affix my signature.

WALDEMAR F. MAYER.
